CLAIM

The ornamental design for a combined sprayer and massager, as shown.

DESCRIPTION

FIG. 1 is a perspective view of a combined sprayer and massager showing the new design;

FIG. 2 is a front elevational view of the design;

FIG. 3 is a rear elevational view of the design;

FIG. 4 is a right side elevational view of the design, wherein the left elevational view is substantially identical;

FIG. 5 is a top plan view of the design; and,

FIG. 6 is a bottom plan view of the design.

FIG. 1

FIG. 2

FIG. 3

FIG. 5

FIG. 6

FIG. 4
